(57) **CLAIM**

The ornamental design for a bottle, as shown and described.

DESCRIPTION

FIG. 1 is a top perspective view of a bottle according to the present invention;

FIG. 2 is a front view of the bottle of FIG. 1;

FIG. 3 is a back view of the bottle of FIG. 1;

FIG. 4 is a right side view of the bottle of FIG. 1;

FIG. 5 is a left side view of the bottle of FIG. 1;

FIG. 6 is a top view of the bottle of FIG. 1; and,

FIG. 7 is a bottom view of the bottle of FIG. 1.

The broken lines shown in the drawings depict portions of the bottle that form no part of the claimed design.
